[54] **BLOCK COPOLYMER PARTICLE FORMING
PROCESS**

[76] Inventor: **John E. Gorman**, 5422 Olympia
Fields Lane, Houston, Tex. 77069

[21] Appl. No.: **696,257**

[22] Filed: **June 15, 1976**

[57]

ABSTRACT

A process is provided for the formation of block copolymer particles having a reduced tendency to agglomerate which comprises extruding the block copolymer into a water bath in the presence of water-dispersible polyvalent metal salts of higher fatty acids and/or water-dispersible surfactants and forming nibs, pellets or strands in the bath. Suitable water soluble surfactants include anionic, cationic and non-ionic surfactants. Especially contemplated is the use of zinc stearate as the surfactant.
